LEVI S. LONGENECKER, OF PITTSBURGH, PENNSYLVANIA.

REFRACTORY BLOCK USED IN BUILDING METALLURGICAL FURNACES.

Application filed January 26, 1925. Serial No. 4,903.

This invention relates to refractory blocks such as are used in building metallurgical furnaces, and more particularly, although not necessarily, to blocks for use in constructing 5 roofs for open hearth furnaces and other places where the blocks are subjected to high temperatures.

An object of this invention is to produce an improved block or tile of the character 10 indicated, provided with means in the nature of tongues and grooves for uniting a series of blocks together in such a way that if one or more of the same are broken, the broken 15 portions will be prevented from falling out of the roof or other structure in which the blocks are placed.

This invention is the result of experience with open hearth furnace roof tiles which are commonly laid up in multiple series of 20 adjacent arches or rings. In such structures, the blocks are held in place mainly by pressure between their engaging surfaces and without the use of cement or other bonding material. When arches such as these are exposed 25 to the heat of the furnace, the lower ends of the blocks, which are more intensely heated than the upper ends, deform more than the upper ends, with the result that the lower ends of the blocks may hang more or less freely. On account of the strains set 30 up in the blocks by reason of the unequal heating of their upper and lower ends, many of the blocks, and in some cases a majority of them, become cracked at some point and 35 fragments thereof become detached and fall away from the roof. The whole life of a roof ring and very often the whole life of the furnace may thus depend on a single tile.

There is no practical way now known of 40 detecting weak tiles before they are installed. When the tiles are built into a roof, the weaker tiles are the first to break and give way. When a broken tile once loses its lower end, which is glazed and which affords 45 protection to the upper part of the tile, the flame of the furnace quickly attacks the unprotected upper part and rapidly burns this part away. It is commonly said in the open hearth furnace industry that when once the 50 original glazed surface of a tile is lost, the

tile simply burns away and that it is very seldom that a tile will again reglaze.

According to the present invention, I prevent the falling away of broken parts of furnace roof tiles by causing the tiles to inter-engage so that if tiles are broken the parts will be caught and prevented from falling out of the roof. In this way the glazed ends of broken tiles are retained and shield the parts from which they are broken 55 from the intense action of the furnace flames. I accomplish this result, in a general way, by forming the tiles with oppositely arranged tongues and grooves which taper upwardly from the bottom of the tile toward 60 the top thereof. These tongues and grooves are, for convenience, preferably made in the form of regular triangles, but other forms will give similar results, provided the tongues and grooves are relatively small at 65 their upper ends and wide toward the lower end of the tile, to afford a support for any portion of the tile which may be broken off below the upper ends of the tongues and 70 grooves.

For a further understanding of this invention, reference may now be had to the accompanying drawing, in which Fig. 1 is a fragmentary vertical sectional view taken through a portion of a furnace roof ring or 75 arch composed of blocks constructed in accordance with this invention; Fig. 2 is a bottom plan view of a portion of the structure shown in Fig. 1; Fig. 3 is an enlarged perspective view of one of the tiles shown in 80 Figs. 1 and 2; Fig. 4 is an inverted perspective view similar to Fig. 3; and Fig. 5 is an enlarged vertical sectional view showing the manner in which a broken tile is 85 retained in place by the tongues and grooves.

Referring first to Figs. 3 and 4, the numeral 2 indicates the body of a refractory block or tile, having a triangular tongue 3 formed on one of its sides. A groove or recess 4, corresponding in shape and position 90 to the tongue 3, is formed in the opposite side of the block 2, and is of sufficient size to admit the tongue 3 of another similar block. The tiles shown in these figures are 95 relatively thin, and it will be understood that 100

the tongue and groove construction here shown is intended to be applied to all other shapes of blocks and tiles which make up a full line of refractories.

5 Figs. 1, 2 and 5 show a number of tiles 2 laid up to form an arched roof ring. It will be observed that the grooves 4 are deep enough and wide enough to allow a certain amount of clearance between the tongues and 10 grooves as shown at 8, Figs. 2 and 5. This permits the use of cement between the blocks, if desired, and also allows some relative adjustment of the individual blocks.

15 The tongues 3 and the grooves 4 may extend either the full length of the blocks or for any desired fraction of their length. As shown in the drawing, these tongues and grooves occupy about three-fourths of the total height of the block, and this proportion 20 I have found to be entirely satisfactory in actual use. It will be understood that this invention is not confined to these particular proportions, and that the tongues and grooves may be made shorter or longer 25 if desired.

Fig. 5 shows what happens when one of the tiles 2 becomes broken at some point between its lower end and the tops of the tongues and grooves. In this figure the 30 break between the parts of the broken tile is shown at 9. It will be observed that the lower part of the tile has fallen down a distance determined by the clearance of the adjacent tongues and grooves. On account 35 of the downwardly flaring shape of the tongues and grooves, the broken part 10 of the tile is held in the position shown in Fig. 5. The broken part is prevented from slipping out sidewise by the rings on opposite 40 sides of the ring which includes the broken tile, and the grooved side of the broken part cannot slip off the tongue inasmuch as the endwise pressure or ring load will hold the tiles together. In this position the lower 45 end of the broken part 10, which is the glazed end of the tile, protects the upper part 11 from the action of the furnace flames, and for this reason, the roof remains, for 50 all practical purposes, as strong as it was before the tile was broken.

In assembling a furnace roof ring of the type illustrated herein, it is necessary to insert key-blocks or driving blocks at suitable intervals, and these blocks are made 55 like the blocks shown in the drawing, except that one face of the block is left smooth. For convenience I provide some key or driving blocks with grooves only and some with tongues only, so as to suit all conditions of use.

The thickness of the tongues and grooves is not important, provided they are thick enough to obtain the proper interlocking between the tiles, and are not so thick as to 65 weaken the tiles.

In the construction shown, the base of the tongue occupies about one-half of the face of the block, and while I have found this to be suitable, it is subject to variation as may be desired.

The blocks provided with tongues and grooves according to this invention may be laid up by the mason as quickly as smooth blocks, and their cost of manufacture is not greatly in excess, since no additional material nor labor is required.

I am aware that blocks have been made with interengaging projections and depressions of various kinds, but in all such cases that are known to me, the function of the interengaging portions is to hold the blocks in position when they are originally put in place. The tongues and grooves of this invention have no such function since the blocks will be held together when first assembled, whether the tongues and grooves are present or not. It is only when displacement occurs, by the breaking of a block or otherwise, that the tongues and grooves become effective in maintaining the continuity of the structure made up therefrom.

As stated above, the regular triangular shape of the tongues and grooves is preferred, as this shape lends itself most easily to convenient manufacture and assembly. 95 However, the sides of the tongues and grooves may be curved either inwardly or outwardly as desired, or given any other shape which provides increasing width toward the bottom of the block.

Refractory blocks are made in a variety of shapes and sizes, some having parallel sides and others being tapered to a greater or less extent for use in arches of various sizes. This invention is of course applicable 105 to all of these various shapes and sizes.

This invention is not restricted to the use of any particular material, but may be applied to blocks made of silica, clay, magnesite, chrome or any other suitable material. Neither is it restricted to blocks for use in making arched roofs, since flat roofs, while they are suspended from hangers instead of being self-supporting, present much the same problems as arched roofs. The improved blocks have the same advantages in both cases. It will also be understood that the construction herein shown may be employed in making blocks for purposes other than refractory roofs and is applicable whenever it is desired to prevent blocks or fragments of blocks from substantial movement relative one to the other, as in floors, roads, pavements and the like, and that no limitations are to be imposed upon this invention except such as are indicated in the appended claims.

I claim as my invention:—

1. A furnace roof composed of refractory blocks arranged side by side and held to-

- gether mainly by pressure between their engaging surfaces, said blocks being interconnected by means of tongues and grooves extending in a generally vertical direction, the said tongues and grooves being narrower at one end than at the other, and thereby operating to prevent broken fragments of said blocks from falling away from said roof.
2. A furnace roof composed of refractory blocks arranged side by side and interconnected by means of tongues and grooves of generally triangular form and having their apexes uppermost, the said tongues and grooves operating to prevent broken fragments of said blocks from falling away from the roof.
3. A furnace roof composed of refractory blocks arranged side by side and held together mainly by pressure between their engaging surfaces, said blocks being interconnected by means of tongues and grooves extending in a generally vertical direction, the said tongues and grooves being narrower at one end than at the other, and thereby operating to prevent broken fragments of said blocks from falling away from said roof, the edges and top portions of said tongues and grooves being modified to prevent chipping of said edges and top portions and to facilitate the manufacture of said blocks and molds.
4. A furnace roof composed of refractory blocks arranged side by side and held together mainly by pressure between their engaging surfaces, said blocks being interconnected by means of triangular tongues and grooves extending in a generally vertical direction, said tongues and grooves operating to prevent broken fragments of said blocks from falling away from said roof, and the said grooves being sufficiently wider and deeper than said tongues to provide clearance therebetween when the blocks are assembled together.
45. 5. A refractory block provided on one of its faces with a triangular projection having its base at one edge of said face, the said block being also provided with a recess or groove on its face opposite to said projection, the said groove conforming in position and shape to said projection.
6. A refractory block having on one of its faces an integral projection or tongue extending from one edge of said face and progressively narrowing toward the opposite end of said face, the said block also having in its opposite face a recess or groove conforming in position and shape to said projection, the edges and apexes of said tongues and grooves being modified to prevent chipping of said edges and apexes and to facilitate manufacture of said blocks and molds.
7. A furnace roof composed of refractory blocks arranged side by side, and means for interconnecting the lower ends of said blocks to prevent broken fragments thereof from falling from said roof.
8. A furnace roof composed of refractory blocks arranged side by side, said blocks being retained in place mainly by pressure between the engaging surfaces of said blocks, and means for interconnecting the lower ends of said blocks to prevent broken fragments thereof from falling from said roof.
9. A furnace roof composed of refractory blocks arranged side by side and held together mainly by pressure between their engaging surfaces, said blocks being interconnected by means of tongues and grooves extending in a generally vertical direction, the said tongues and grooves being narrower at their tops than at their bottoms, and thereby operating to prevent broken fragments of said blocks from falling away from said roof.
10. A furnace roof composed of refractory blocks arranged side by side and interconnected by means of tongues and grooves of generally triangular form and having their apexes uppermost, the said tongues and grooves operating to prevent broken fragments of said blocks from falling away from the roof.
11. A furnace roof composed of refractory blocks arranged side by side and held together mainly by pressure between their engaging surfaces, said blocks being interconnected by means of tongues and grooves extending in a generally vertical direction, the said tongues and grooves being narrower at their tops than at their bottoms, and thereby operating to prevent broken fragments of said blocks from falling away from said roof, the edges and top portions of said tongues and grooves being modified to prevent chipping of said edges and top portions and to facilitate the manufacture of said blocks and molds.
12. A furnace roof composed of refractory blocks arranged side by side and held together mainly by pressure between their engaging surfaces, said blocks being interconnected by means of triangular tongues and grooves extending in a generally vertical direction, said tongues and grooves operating to prevent broken fragments of said blocks from falling away from said roof, and the said grooves being sufficiently wider and deeper than said tongues to provide clearance therebetween when the blocks are assembled together.
13. An integral block having on one of its faces a retaining portion offset from the plane of said face, said offset portion extending upwardly from the base of the block and widening progressively from one end to the other.
14. A block having on one of its faces an integral projection or tongue which, when the block is in use, extends in a generally

vertical direction from the base of the block and widens progressively from its top to its bottom, said block also having, in its face opposite to said projection, a recess or groove conforming in position and shape to said projection.

15. A refractory block having an integral triangular projection formed on one of its faces and a triangular recess or groove formed in the opposite face of said block and opposite to said projection.

16. A refractory block provided on one of its faces with a triangular projection having its base at one edge of said face, the 15 said block being also provided with a recess or groove on its face opposite to said projection, the said groove conforming in position and shape to said projection.

17. A refractory block having on one of 20 its faces an integral projection or tongue extending from one edge of said face and progressively narrowing toward the op-

posite end of said face, the said block also having in its opposite face a recess or groove conforming in position and shape to said 25 projection, the edges and apexes of said tongues and grooves being modified to prevent chipping of said edges and apexes and to facilitate manufacture of said blocks and molds.

18. A refractory block having on one of its faces an integral triangular projection or tongue having its base at one edge of said face, the said projection extending from a small fraction of the length of said block 30 to the full length of said block, and the said block being also provided on its opposite face with a recess or groove conforming in position and shape to said projection.

In testimony whereof, I have hereunto 40 subscribed my name this 19th day of January, 1925.

LEVI S. LONGENECKER.
